MECHANICAL PROJECTING APPARATUS

Nelson J. Quinn, Toledo, Ohio, assignor of one-half to Horace B. Fay, Shaker Heights, Ohio

Application November 2, 1936, Serial No. 108,803

4 Claims.

(CL. 51—9)

The present invention relates to a centrifugal machine for projecting finely divided abrasive particles at abrading velocities.

In accordance with this invention, a supporting disc or head is provided which is suitably mounted, as on a shaft, for high speed rotation. The disc or head carries a plurality of spaced blades. Means are provided for feeding abrasive material to the heels of the blades during a predetermined arc of rotation thereof so that the blades receive the abrasive while rotating at comparatively low velocity, the rotating blades then serving to accelerate the abrasive and project the same from the outer ends thereof at abrading velocities.

An object of this invention is to reduce the percentage of abrasive destroyed in operation without doing useful work, and to so feed the abrasive to the blades that the abrasive projected by the blades from the outer ends thereof will be controlled as to direction.

My improved centrifugal machine may comprise a rotatably mounted disc supporting radially extending blades, or it may comprise a pair of rotatable discs coaxially mounted in spaced relationship, each disc supporting a set of radially extending blades on the facing sides thereof. Between the two sets of blades may be located means for feeding abrasive to the inner ends or heels of the blades. The feeding means may be adjusted or moved into various positions so that the abrasive material is projected thereby into the path of rotation of the blades at a predetermined point during rotation thereof, whereby directional control of the abrasive thrown by the rotating blades is achieved.

The abrasive feeding means in accordance with this invention extends from a point beyond the outer ends of the blades inwardly toward the shaft and substantially perpendicular to the shaft axis, and is operative to discharge the abrasive into the path of rotation of the blades adjacent the inner ends thereof. Power driven means may be provided for conveying and forcibly ejecting the abrasive into the path of rotation of the blades.

A more detailed description of my invention will follow in the specification which is to be interpreted by reference to the annexed drawing. The salient features of my invention will be set forth in the claims.

Referring now to the drawing:

Fig. 1 is a transverse cross-sectional view of my improved centrifugal abrasive projecting machine as it appears when looking in the direction of the arrows 1—1 of Fig. 2;

Fig. 2 is a sectional view through the machine showing only one of the two bladed rotor discs or heads, this view illustrating in more detail the abrasive feeding device as it appears when look-

ing in the direction of the arrows 2—2 of Fig. 1;

Fig. 3 shows a bladed rotor head equipped with a feed belt for feeding the abrasive into the path of rotation of the blades;

Fig. 4 shows a bladed rotor head and an abrasive feeding wheel provided with a hollow abrasive feeding rim operative to feed abrasive material to the blades; and

Fig. 5 shows a bladed rotor head and abrasive feed wheel associated therewith operative to throw the abrasive material into the path of rotation of the blades.

The projecting apparatus about to be described is supported upon a suitable stationary base, not shown, which carries a horizontal shaft 10 which may be rotated in any desired manner. A pair of spaced disks 15 are carried by the shaft and fixed thereto by end plates 17, each of which is rigidly fastened to the shaft and to its respective disk 15. These disks act as outside retaining walls to prevent an overflow of abrasive at the sides of the projection device and greatly increase the throwing efficiency by causing all ejection to take place at the outer periphery of the blades.

A sleeve 18 is provided to space the disk members 15 and to provide a support for the abrasive feeding means hereinafter described.

Projection blades are carried by the disks which direct the stream of abrasive outwardly to the surface to be cleaned. These blades may comprise trough-shaped members 20 which are brazed to angle flanges 22, which in turn are secured to the face of the respective disks 15 by suitable cap screws. A plurality of these blades are mounted about the face of each disk and cooperate with oppositely located blades carried by the other disk to provide the aforementioned projecting means.

The power feeding means heretofore mentioned may comprise, as shown in Figs. 1 and 2, a tube 25 carrying a feed screw 27, operable at various speeds depending on the amount of abrasive to be fed and which, at its lower end, tapers to form a bearing portion engaging an axially located journal in the end of the tube 25. A pair of openings 28 are provided on opposite sides of the tube 25 for the discharge of abrasive fed thereto under the action of the screw 27.

The end of the tube 25 terminates in an ear which is pivotally carried by the pin 32 between the ears of a clip 34, as shown in Fig. 2. The opposite end of the clip 34 surrounds the shaft sleeve 18, as shown in Fig. 1, and is rotatably secured in position thereon by a second sleeve 35 secured to the aforementioned sleeve and the shaft 10 by a pin 37.

The tube 25 passes upwardly from the clip 34 between the cooperating blades 20 of respective disks 15 and at its top terminates in a feed funnel 40, through which the supply of abrasive is

admitted to the tube. This upper end of the tube 25 is adjustably carried by the main frame of the machine in a manner to permit rocking of the lower end of the tube to locate the openings 28 at various points about the shaft 10 in order to effectively control the stream of abrasive discharge from the machine.

A belt feed may be provided, as shown in Fig. 4, in the nature of a modification of my preferred form to positively transfer a given amount of abrasive to the heels of the projecting blades. As shown in that figure, one end of a hollow V-belt 45 passes around a pulley 47 located beyond the disks 15 and adjacent a feed funnel 50 which deposits abrasive on the belt 45. The opposite end of the belt 45 passes around a straight sleeve fixed to the shaft 10, serving also to space the disks 15 and is positively rotated thereby. As will be seen in Fig. 4, abrasive passing down the belt 45 is discharged to the heels of the projecting blades at such a point as to result in a downward blast of abrasive from the disks. The guide pulley 47 is adjustable vertically to vary the point of discharge at the inner end from the belt and thus control the direction of the stream of abrasive discharged from the machine.

A further modification is shown in Fig. 4, where a feeding wheel 60 provided with a rim 61 of V-shaped cross-section is positively rotated and discharges abrasive material onto the heels of the blades as there shown. Where two sets of abrasive throwing wheels are co-axially mounted on the same shaft 10, the feeding wheel 60 is so positioned as to extend axially therebetween with the plane of rotation of the feeding wheel substantially perpendicular to the axis 10 of the spaced throwing wheels, each throwing wheel comprising a disk 15 having a plurality of radially extending blades 20 mounted thereon. Abrasive is deposited in the rim at the top of the wheel by means of an abrasive supply funnel 62, as shown in Fig. 4. The wheel 60 is rotated at any desired speed, although necessarily much slower than is the speed of the disks 15, and this speed may be varied to deposit abrasive at the blades in greater or lesser amounts as desired. Further, the wheel 60 may be shifted to a certain extent around the axis of the shaft 10 to vary the point of discharge of the abrasive material and in this way control the direction of the sand blast leaving the machine.

An additional modification of my feeding means is shown in Fig. 5, where a small wheel 70 is provided carrying a plurality of deep pockets into which abrasive is dumped by a suitable funnel 75. The wheel 70 is rotated at a rapid rate and projects the abrasive into the path of the large blades 30 of the disks 15, from whence it is thrown at the required speed onto the work to be cleaned. The small wheel 70 may be frictionally driven from the disks 15, or if desired may be rotated by a small motor of suitable construction or driven in any other desired manner. The wheel 70 may be shifted about the periphery of the disks 15 to vary the point at which abrasive thrown therefrom is picked up by the blades 30 and to control in this manner the direction of discharge of the abrading material from the machine.

From the foregoing specification it will be seen that I have provided a positive means for feed-

ing abrasive to the heels of the projecting blades of a discharge wheel. It will be further seen that by reason of positively feeding the material between the blades of a pair of coaxially mounted disks it is possible to operate this type of abrading machine at a greatly increased efficiency. Furthermore, adjustment of the feeding means renders it possible to control the direction of the stream of abrasive as the same leaves the machine. The amount of power required to drive the apparatus is of course decreased because of the closed system set up due to the use of the side-wall retaining disks, as distinguished over the old type of paddle wheel which set up a very strong fanning action.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a machine for projecting abrasive, the combination of a rotatable shaft, a support carried by said shaft, a plurality of blades carried by said support, and a power operated feeding belt for conveying abrasive material from beyond the blades inwardly toward said shaft and substantially perpendicular to the shaft axis and discharging the abrasive material into the path of rotation of the inner ends of the blades, said belt being adjustable to control the direction of discharge of said abrasive.

2. In a machine for the projection of abrasive, the combination of a rotatably mounted shaft, a pair of coaxially spaced blade supports mounted on said shaft, a plurality of projector blades carried by each support with the blades on one support spaced from the blades on the other support, and power operated feed belt extending between said supports and said blades generally perpendicular to said shaft for positively feeding and discharging abrasive into the path of rotation of the inner ends of said blades as they arrive at a predetermined point during rotation thereof.

3. In a centrifugal abrasive projecting machine, a rotatably mounted shaft, a disk shaped support fixed to rotate with said shaft, spaced abrasive propelling blades carried by said support and projecting laterally from one face thereof, a power-operated feed belt extending from a point exterior to said support to a point adjacent the path of rotation of said blades for positively feeding abrasive into the path of rotation of the inner ends of said blades as they arrive at a predetermined point during rotation.

4. In a centrifugal abrasive projecting machine, a rotatably mounted shaft, a disk shaped support fixed to rotate with said shaft, spaced abrasive propelling blades carried by said support and projecting laterally from one face thereof, a power-operated feed belt extending from a point exterior to said support to a point adjacent the path of rotation of said blades for positively feeding abrasive into the path of rotation of the inner ends of said blades as they arrive at a predetermined point during rotation, the inner end of said belt being trained around and supported by said shaft.
